UNITED STATES PATENT OFFICE.

LOUIS BOND CHERRY, OF KANSAS CITY, MISSOURI.

SYNTHETIC PRODUCTION OF HYDROCARBON COMPOUNDS.

1,229,886.

Specification of Letters Patent. Patented June 12, 1917.

Application filed February 21, 1916. Serial No. 79,763.

To all whom it may concern:

Be it known that I, LOUIS BOND CHERRY, a citizen of the United States, and resident of Kansas City, Jackson county, and State 5 of Missouri, have invented certain new and useful Improvements in Synthetic Production of Hydrocarbon Compounds, of which the following is a specification.

This invention relates to certain improvements in and relating to the synthetic production of hydrocarbon compounds by electrochemical action; and the objects and nature of the invention will be readily understood by those skilled in the art in the 10 light of the following disclosure of the preferred mechanical expression and method of practising the invention.

I have discovered that a re-arrangement of the molecular structure of a hydrocarbon 20 compound can be brought about to change the boiling point and gravity thereof, by subjecting such compound to the silent discharge of a bipolar oscillatory high-frequency electric current and that the boiling 25 point and gravity of the compound produced can be varied by varying the frequency of the current applied; and furthermore, that a relatively low gravity hydrocarbon compound can be so changed as to produce a 30 compound of higher gravity and of lower boiling point by subjecting such low gravity compound to said electric discharge when said low gravity compound is in a vaporized state and mechanically mixed with a small 35 proportion of a high gravity low boiling point hydrocarbon compound; and furthermore, that a high gravity low boiling point hydrocarbon (such as casing head gasoline) can be so changed as to produce a 40 product of lower gravity and higher boiling point, by subjecting the same to such electric discharge while said high gravity compound is in a vaporized state and mechanically mixed with a small proportion of a relatively 45 low gravity high boiling point hydrocarbon compound.

My discovery is of peculiar value and importance when applied to hydrocarbon compounds of the paraffin series following the 50 common formula (C_nH_{2n+2}) as I am enabled to raise any of the solid or liquid compounds of said series to a higher position in the series by the addition of still higher gravity hydrocarbon liquid or gas without the substantial 55 destructive distillation, precipitation of carbon or release of free gas that

takes place in the commercial methods now generally practised in producing hydrocarbon of like quality.

In practising my invention, the fluid or 60 fluids in the vaporized or gaseous states or both, is or are passed through a bipolar oscillatory high frequency silent electric discharge or the equivalent thereof, and a re-arrangement of the molecular structure or 65 structures thereof is thereby brought about to either increase or decrease the proportion of hydrogen in the resulting compound without the waste incident to destructive distillation. I usually pass the vaporized or 70 gaseous hydrocarbon compound or compounds through a peculiar electric field or an electric treating chamber provided with separated electrodes along or between which the fluid flows so that the fluid will be sub- 75 jected for a more or less extended period of time to the silent electrical discharge oscillating back and forth between said electrodes and across the intervening space.

This treating chamber is usually arranged 80 to constitute a portion of the offtake or outlet passage from any suitable still in which the hydrocarbon fluids are brought to the desired or any suitable temperature under any suitable pressure, which temperature and 85 pressure are also approximately maintained in said treating chamber. I usually pass or discharge the fluids from said treating chamber directly into any suitable condenser from which the final liquid product can be 90 discharged in any suitable manner.

The frequency of the electric current discharge during the operation, will be varied, through the medium of suitable adjustable instrumentalities employed, according to the 95 temperature and pressure in the treating chamber and the boiling point and gravity desired in the final product. These various conditions may vary during the operation and according to the particular compounds 100 being treated, and hence I usually test the first portion of the product delivered from the condenser and then vary the frequency of the electric current until the desired result is secured.

In the accompanying drawings I have diagrammatically illustrated apparatus that can be employed for practising my invention. In these drawings, I have indicated any suitable still 1, provided with any suitable heating means 2, and having any suitable discharge or offtake pipe or connection 105 110

3, forming a treating chamber 4, and leading to and discharging into any suitable condenser 5.

In the particular diagram illustrated, I 5 show a fluid supply pipe 6, opening into said still through the bottom thereof, and another fluid supply pipe 7, for discharging a different fluid into the lower portion of the interior of the still; said last mentioned pipe 10 having an extended perforated portion or length arranged within the still for more or less uniformly distributing the fluid flowing from the pipe throughout the body of fluid in the still, although my invention is not so 15 limited.

In the particular example illustrated, the treating chamber is arranged within the still and above the liquid level so as to be subject to the same temperature and pressure conditions 20 that exist in the still. In this example, this treating chamber consists of metal or other good conductor of electricity, and has an elongated portion or extended length arranged within the still, and is of 25 horizontally elongated pipe or tubular form with an inlet at one end open within the still and forming the discharge opening or outlet from the vapor or gas space of the still. The opposite end of the tubular conducting 30 body or pipe length 8, extends to the exterior of the still and opens into a suitable coupling or union 9, leading to the condenser 5.

In the particular embodiment illustrated, the tubular body 8, forming the surrounding wall of the treating chamber is utilized 35 to constitute or form one of the electrodes, while the opposing electrode 10, is arranged centrally and longitudinally within and approximately throughout the length of said 40 chamber 4, and throughout its length is uniformly spaced from the inner surfaces of the tubular body 8, that forms said chamber. The electrode 10, can be supported by insulators 11, by which said electrode is insulated 45 from the body 8, and from the walls of the still and through which the current can be conducted to said electrode by wires 12. The current can be conducted to the 50 opposing electrode (the body 8) from wire 13, through an insulator 14, so that the electrode 8, will be thoroughly insulated from the electrode 10, as will be readily understood by those skilled in the art, although I 55 do not wish to limit my invention to the arrangement of electrodes, wiring and insulators illustrated.

The power is supplied through wires 15, 16, from any suitable source of preferably alternating current and is supplied to the 60 wires 12, 13, through the medium and control of any suitable adjustable inductive resistance 17, any suitable high tension transformer 18, any suitable adjustable condenser 19, any suitable spark gap 20, any suitable 65 (either adjustable or non-adjustable) oscilla-

tion or high frequency transformer 21, or otherwise, to produce a bipolar oscillatory high frequency silent electric discharge across the treating chamber back and forth between the electrodes 8, 10. According to 70 my present understanding of my invention and discovery the current should be of such nature and so controlled as to avoid sparking or arcing and to provide the oscillatory silent discharge of high voltage and high 75 frequency, and yet so that the current is under convenient manual control to permit varying the frequency thereof to suit the peculiar conditions that may arise during any operation and the particular hydrocarbon 80 compound product desired, and yet I do not wish to so strictly limit all features 85 of my invention.

In practising my invention, the hydrocarbon fluids are introduced into the still 85 through the pipes 6, 7, and the liquid level is maintained below the discharge 3, from the still. The necessary heat is applied to the still to vaporize all of the volatile portions of the liquids therein preferably avoiding precipitation of carbon and freeing of gases and consequent waste and breaking down of compounds. I usually maintain more or less pressure in the still although the presence or absence of pressure will depend on the particular fluids being treated 90 and the particular results being sought.

The vapors and gases are mechanically mixed and uniformly heated and pass from the still through the treating chamber 100 wherein they are subjected while under the heat and pressure in the still, for a more or less extended period of time to any electrical discharge which will cause a re-arrangement 105 of their molecular structure and produce a hydrocarbon compound having a boiling point and gravity differing from those of the hydrocarbon compounds introduced into the still. The voltage of the electric current will be such that the greatest amperage will 110 pass through the fluids between the electrodes without causing arcing, and in practice probably runs upward of five thousand volts where the electrodes are not less than two inches apart. The frequency employed 115 will vary according to the distance between the electrodes and the gravity and boiling point of product desired and may run to upward of one million cycles per second, although my invention is not so limited. In 120 this connection, I have found that it takes a higher frequency to produce the higher gravity low boiling point compounds than the lower gravity higher boiling point products. If I desire to raise the gravity and 125 lower the boiling point of a comparatively low gravity hydrocarbon distillate of the paraffin series, the liquid compound is introduced into the still through the pipe 6, (if need be under the required pressure to 130

overcome the pressure in the still) and the flow of liquid is controlled and is approximately constant to maintain the desired liquid level in the still as the liquid is 5 vaporized in the still and passed off through the electric treating chamber.

During the operation of the still, a constant flow of either free hydrogen or hydrogen carrying gas or compound is discharged 10 into the liquid in the still through pipe 7, to supply a volume of such compound or gas that will be heated by its passage through the liquid to the same temperature as the vapor rising from the liquid and so as 15 to become mechanically mixed with the vaporized distillate and flow therewith into the electric treating chamber and supply the hydrogen to unite with the distillate vapor and produce the fluid hydrocarbon product 20 which will be of different molecular structure from either of the compounds originally introduced into the still and will be of lower boiling point and higher gravity than the distillate originally introduced into the 25 still.

The hydrogen carrying compound introduced through pipe 7, is preferably a high gravity volatile hydrocarbon liquid, or a gas, such as natural gas. 30 The still is so operated and controlled as to reduce to the minimum all possibility of destructive distillation and "cracking," and to avoid precipitation of carbon, and consequently the still is preferably covered at the 35 top or otherwise arranged and provided with heat insulating materials to prevent condensation within the still.

It is not necessary to maintain or predetermine any particular proportioning between the volume of distillate and the 40 volume of gas introduced through pipes 6 and 7, except to provide a surplus volume of gas, that is, more gas than is taken up by or combined with the vaporized distillate. The 45 surplus gas passes over with the final hydrocarbon product and is trapped at the condenser discharge.

In the particular diagram shown, the product from the condenser discharges into 50 a trap or separating chamber 23, in which the liquid settles to the bottom and can be drawn off through valved pipe 24, while the surplus or unconsumed gas rises to the top of the chamber and can be drawn off 55 through valved pipe 25. Usually the compressor (not shown) that forces the gas into the still through pipe 7, also draws the surplus gas from pipe 25, and discharges the same back again into the still. The operator 60 can by observing gage 26, on trap 23, determine whether to increase or diminish the volume of gas discharged into the still.

The peculiar electric discharge excites the vapor and gases and causes re-arrangement 65 of the molecular structures thereof during

which re-arrangement the structural elements are attuned or brought into step to produce a new molecular structure of the same series as that of the distillate but having a higher percentage of hydrogen, and 70 this re-arrangement takes place without material loss of carbon, and is brought about by controlling the rate of frequency of the peculiar electric discharge. The rate of frequency of the electric discharge must be 75 under the control of the operator so that he can vary the same until he produces a product of the particular gravity and boiling point desired.

As a specific example of the application 80 of my method to hydrocarbon compounds of the paraffin series, if one volume of pentadecane ($C_{15}H_{32}$) is introduced into the still through pipe 6, to every two volumes of methane (CH_4) introduced into the still 85 through pipe 7, and the mechanical mixture of the resulting vapor and gas rising from the liquid in the still is passed through the peculiar electric field hereinbefore described under proper heat and pressure conditions, 90 a resulting liquid product will be drawn from the pipe 24, of the condenser consisting of two volumes of octane (C_8H_{18}) while one volume of methane (CH_4) will be drawn from pipe 25 for return into the liquid in 95 the still through pipe 7. In this instance, approximately the following reaction takes place

The boiling point and specific gravity of each of the just mentioned compounds of the paraffin series are well understood by those skilled in the art who will also appreciate the fact that, in the example mentioned, 105 I have through my method produced a liquid product of the paraffin series having a comparatively high gravity and low boiling point with respect to the corresponding characteristics of the liquid compound introduced into the still and that a substantial gain in hydrogen percentage has been made over said comparatively low gravity liquid introduced into the still. 110

The references herein made to high and 115 low gravity refer to Baumé scale hydrometer readings and to the gravity ratings of hydrocarbon compounds of the paraffin series wherein pentadecane is accorded a specific gravity of approximately 38° Bé. and a boiling point of approximately 496.4° Fah. and much higher in the series, appears octane with a specific gravity of approximately 69° Bé. and boiling point of approximately 254° Fah. 120

Desiring to protect my discovery and invention in the broadest manner legally possible, what I claim is:

1. The method of causing re-arrangement of the molecular structures of liquid hy- 130

drocarbon compounds to produce a product of the same series but of different gravity and boiling point by subjecting such compounds while in a vaporized state to the 5 silent discharge of a high frequency oscillating bipolar electric current or its equivalent, substantially as described.

2. The method of causing a re-arrangement of the molecular structure of a hydrocarbon compound to vary its percentage of hydrogen without loss of carbon which consists in subjecting such compound to the silent discharge of a high frequency oscillating bipolar electric current in the 10 presence of a different compound of the same series and while said compounds are maintained under a vaporizing temperature, substantially as described.

3. In the electrochemical method of treating liquid hydrocarbon compounds, that step which consists in subjecting such compounds to the silent discharge of a high frequency oscillating bipolar electric current, in the simultaneous presence of a vaporizing temperature and an agent for supplying hydrogen to unite with said compound to produce a final product of different gravity and boiling point from the compound originally treated, substantially as 15 described.

4. The method of producing a relatively high gravity hydrocarbon product by the addition of hydrogen to a comparatively low gravity hydrocarbon liquid without loss 20 of carbon, which comprises subjecting said liquid while being maintained in a hot vaporized state to the silent discharge of a high frequency bipolar oscillating electric current in the presence of a hot hydrogen 25 supplying gaseous agent.

5. The method of treating liquid hydrocarbon compounds which consists in vaporizing the same and then passing the same while heated through the silent discharge 30 of a high frequency bipolar oscillatory electric current and then condensing the same.

6. The method of treating liquid hydrocarbon compounds to produce different gravity and boiling point hydrocarbon products which consists in subjecting such compounds to the silent discharge of a bipolar high frequency oscillatory electric current and varying the frequency of such current to obtain a product of an approximately 35 determined gravity and boiling point.

7. The method of treating low gravity liquid hydrocarbon compounds to produce high gravity hydrocarbon compounds which consists in producing a mechanical mixture 40 of such compounds and a smaller proportion of a higher gravity hydrocarbon compound and then causing a re-arrangement of the molecular structures of such compounds without precipitation of carbon to produce 45 a product having a higher percentage of

hydrogen than contained in the original liquid compound by subjecting such mixture in the presence of a vaporizing temperature to a high frequency oscillatory electric current discharge, substantially as described. 70

8. The method of treating a liquid hydrocarbon compound which consists in vaporizing the same and heating and mixing a hydrocarbon gas therewith and then treating 75 the mixture of vapor and gas in the presence of heat with the silent discharge of a high frequency oscillatory electric current and then passing the resulting product through a condenser. 80

9. The method of treating liquid hydrocarbon compounds which consists in introducing the same into a still, introducing a hydrocarbon gas into said liquid in the still, heating the liquid to vaporize the same and to heat the gas and mechanically mix the gas and vapor, subjecting the mixture of gas and vapor while under the heat and pressure conditions in the still to the silent discharge of a bipolar oscillatory high frequency electric current passing the vapor and remaining gas into a condenser, and then separating the resulting liquid hydrocarbon product from any remaining free 90 gas, substantially as described. 95

10. In the electrochemical method of treating hydrocarbon compounds, that step which consists in subjecting such compounds while in the vaporized state to the silent discharge of a high frequency oscillatory bipolar electric current in the presence of an agent for supplying hydrogen to unite with such compound to produce a product of a different gravity from the compound 100 treated, substantially as described. 105

11. The method of treating liquid hydrocarbons of the paraffin series to change the gravity thereof which consists in subjecting the same while in the vaporized state to the silent discharge of a bipolar oscillatory 110 high frequency electric current. 115

12. In the method of treating a low gravity hydrocarbon distillate to produce a high gravity liquid hydrocarbon of the same series as the distillate, vaporizing the distillate and subjecting the same to the silent discharge of a high frequency bipolar oscillatory electric current. 115

13. In the electrochemical treatment of low gravity hydrocarbon distillates, subjecting the distillate while in a vaporized state to the silent discharge of a bipolar oscillatory electric current and manually controlling the frequency of such current to obtain a product of approximately predetermined 120 gravity, substantially as described. 125

14. In the electrochemical treatment of hydrocarbon compounds, subjecting the compound to the silent discharge of a high frequency bipolar oscillatory electric cur- 130

rent and controlling and varying the frequency of such current to obtain a product of a predetermined quality, substantially as described.

15. In the method of treating a low gravity liquid hydrocarbon distillate to produce a high gravity liquid hydrocarbon, vaporizing the distillate without substantial loss of carbon and mixing the vapor with hydrocarbon gas and causing a rearrangement of the molecular structure of the distillate by subjecting the mixture of vapor and gas to a high frequency electric current discharge whereby hydrogen is taken from the gas to produce a liquid hydrocarbon product of relatively high gravity, substantially as described.

16. In the method of treating a liquid hydrocarbon compound of the paraffin series, vaporizing said liquid and introducing a hydrocarbon gas into said liquid while being vaporized to produce a mechanical mixture of the gas and vapor and causing a rearrangement of the molecular structure of said compound by which it takes up hydrogen to produce a product of the paraffin series having a higher percentage of hydrogen than said compound by subjecting such mixture to a high frequency bipolar electric current discharge.

17. In the production of relatively light oils from heavy oils, subjecting the heavy oils while in the vaporized state to a high frequency electric current discharge in the presence of a hydrocarbon gas or vapor relatively rich in hydrogen.

18. In the production of relatively light oils from heavy oils without substantial loss of carbon, subjecting the heavy oils while in the vaporized state to an oscillatory electric current discharge of the necessary frequency in the presence of a comparatively small proportion of hydrocarbon gas or vapor relatively rich in hydrogen.

19. In the production of relatively light oils from heavy oils, subjecting the heavy oils while in the vaporized state to a high frequency bipolar electric current discharge in the presence of a hydrocarbon gas or vapor relatively rich in hydrogen.

20. In the production of relatively light oils from heavy oils without substantial loss of carbon, subjecting the heavy oils while in the vaporized state to a high frequency electric current discharge in the presence of hydrocarbon gas or vapor relatively rich in hydrogen.

21. In the production of relatively light oils from heavy mineral oils without substantial loss of carbon, subjecting the heavy oils while in the vaporized state to the silent discharge of a high frequency electric cur-

rent in the presence of hydrocarbon gas or vapor relatively rich in hydrogen.

22. The art of producing relatively light oils from heavy mineral oils by increasing the percentage of hydrogen in the heavy oils without substantial destructive distillation and loss of carbon, through treatment of said oils, while in the vaporized state and in the presence of a hydrogen supplying agent, by an oscillatory electric current discharge of the necessary frequency.

23. The art of producing relatively light oils from heavy mineral oils by increasing the percentage of hydrogen in the heavy oils without substantial destructive distillation and loss of carbon, through treatment of said oils, while in the presence of a hydrogen supplying agent, by the silent discharge of a high frequency electric current.

24. In the production of low boiling point relatively light oils from heavy oils, that step which consists in increasing the percentage of hydrogen in the heavy oils without substantial loss of carbon through the treatment of such oils in the vaporized state by the silent discharge of an oscillatory electric current of the necessary frequency.

25. In the production of low boiling point relatively light oils from heavy mineral oils, that step which consists in increasing the percentage of hydrogen in the heavy oils without substantial loss of carbon through the treatment of such oils in the vaporized state by the discharge of an oscillatory electric current of the necessary frequency.

26. In the method of treating liquid hydrocarbon compounds of the paraffin series, vaporizing the same without substantial loss of carbon and producing a mechanical mixture of said vapor and a gas or vapor relatively rich in hydrogen, and subjecting said mechanical mixture to the discharge of an oscillatory electric current of the necessary frequency to cause rearrangement of the molecular structures of said compounds to produce a product of the paraffin series having a higher percentage of hydrogen than said compounds.

27. In the method of treating a high specific gravity liquid hydrocarbon distillate to produce a low specific gravity liquid hydrocarbon, vaporizing the distillate without substantial loss of carbon and mixing the vapor with hydrocarbon gas and causing a rearrangement of the molecular structure of the distillate by subjecting the mixture of vapor and gas to a high frequency electric current discharge, whereby hydrogen is taken from the gas to produce a liquid hydrocarbon product of relatively low specific gravity, substantially as described.

LOUIS BOND CHERRY.
